CASING FOR AN ELECTRIC SHAVER

Richard Fischer, Frankfurt am Main, Germany, assignor to Braun Aktiengesellschaft, Frankfurt am Main, Germany, a firm

Filed Jan. 13, 1969, Ser. No. 15,330

Claims priority, application Germany July 15, 1968

Term of patent 14 years

Int. Cl. D28—03

U.S. Cl. D95—3

FIG. 1

FIG. 2

FIG. 4

FIG. 1 is a perspective view of casing for an electric shaver, showing my new design;

FIG. 2 is a left side elevational view thereof;

FIG. 3 is a top plan view; and

FIG. 4 is a bottom plan view.

The appearance of the rear face of the casing for an electric shaver is identical with the front face shown in FIG. 1 and the appearance of the not shown side face of the casing for an electric shaver is identical to the appearance of the side face shown in FIG. 2.

I claim:

The ornamental design for a casing for an electric shaver, substantially as shown and described.
